(57) **CLAIM**

The ornamental design for a curtain roller as shown and described.

DESCRIPTION

FIG. 1 is a front, right and bottom perspective view of a curtain roller, showing my new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view thereof.

FIG. 8 is an enlarged bottom plan view thereof.

FIG. 9 is an exploded view thereof; and,

FIG. 10 is a perspective view of the curtain roller, shown in an environment of use.

The evenly-spaced broken lines shown in FIGS. 1-10 are for purposes of illustrating portions of the curtain roller that forms no part of the claimed design; the additional evenly-spaced broken lines shown in FIG. 10 are for purposes of illustrating environmental subject matter only and forms no part thereof.

1 Claim, 10 Drawing Sheets
